UNITED STATES PATENT OFFICE.

CARL DAVENPORT, OF SHEFFIELD, ENGLAND.

WINDING AND HAULAGE DRUM.

1,110,313.

Specification of Letters Patent. Patented Sept. 15, 1914.

Application filed November 29, 1913. Serial No. 803,663.

To all whom it may concern:

Be it known that I, CARL DAVENPORT, a subject of the King of Great Britain and Ireland, residing at the Aztec Works, Neepsend, Sheffield, in the county of York, England, have invented new and useful Improvements in Winding and Haulage Drums, of which the following is a specification.

This invention relates to winding and haulage drums and in particular to a haulage drum of especial value for use in collieries and generally in connection with mines.

According to my invention I produce a haulage drum which entirely houses the engine or motor, the requisite gearing, and other moving parts, leaving only control mechanism exterior to the drum. I thus accommodate the engine and gearing in a closed casing which affords perfect protection to engine and gear and prevents access of all dirt and dust. Further, this method of locating engine and gear enables me to keep the haulage plant extremely compact, thus economizing space in the mine; to use a system of splash lubrication; and to produce a haulage drum which can be run with an absolute minimum of risk as regards accidents. An additional point is, that with the engine and gearing located within the drum, no tampering by an unauthorized person can occur.

The construction of the new haulage drum will be clearly understood from the following detailed description having regard to the attached drawings, in which:

Figure 1 represents a longitudinal sectional elevation of my new haulage drum or winding apparatus. Fig. 1^a is a detail view. Fig. 2 shows an end elevation of Fig. 1 with the upper half in section. Fig. 3 is a broken longitudinal detail sectional view and shows the passages in the fixed crank shaft and the ports leading to and from the cylinders. Fig. 4 is a cross section of Fig. 3 taken on the line X—X. Fig. 5 shows a detail section of a modification in the fluid distributing sleeve arrangement which may be used in connection with the fixed crank shaft, and Fig. 6 is a longitudinal section of this modified arrangement.

I make use of a winding drum in the form of a turned hollow casting of suitable dimensions and such as is marked 1 in the drawings, and I locate or place therein the motor or engine of whatever type, so that, the motor or engine is entirely accommo-

dated within the interior of the drum 1. I prefer to employ a multi-cylindered engine and I show an engine having three cylinders marked 2. Such an engine is intended to be actuated by compressed air, but steam or other fluid pressure may be used. The cylinders 2 are arranged to revolve around a crank pin 3 forming part of a fixed two armed crank shaft 4. Such fixed shaft 4 is supported by two end bearings 5, 5, from framework such as the steel girders 7, 8, and such shaft is of sufficient strength to sustain the rotatable cylinders 2, 2, 2, which are carried upon disks 9, 10. These disks 9 and 10 along with the cylinders 2, 2, 2, revolve around the fixed crank shaft 4 due to the power developed in the open ended cylinders 2, 2, 2. The connecting rods 11 of the pistons in said cylinders all converge on the crank pin 3 of the fixed crank shaft. The left-hand end of the crank shaft is formed with passages which may be styled inlet and exhaust passages 12 and 13 which communicate (via the chest 14) necessarily with the channels 15, 16, 17 leading to the cylinders and such channels 15, 16, 17 lead both to and from each cylinder but occur only in the revolute disk 9. Upon the boss of the disk 10 I secure a spur pinion 18 and this gears into a spur wheel 19 fixed on a revolute shaft 20 supported by ball bearings at 21 in an extension from the fixed sleeve 22 which carries the right-hand half of the fixed crank shaft 4. The removable right-hand cheek of the drum 1 revolves normally around this fixed sleeve, as Fig. 1 clearly shows. Upon the short shaft 20 is fixed a spur pinion 23 and this gears with a larger internal spur pinion 24 fixed on the drum cheek. Thus, rotatory motion from the two disks 9, 10 can be communicated through the spur gear to the drum and the drum is thereby rotated. Upon the right-hand extremity of the sleeve surrounding the fixed crank shaft 4 I key a clutch pulley 25 which is encircled by a flexible band 26 one end of which is anchored while the other carries an ear 27. A screwed shaft 28 carried in extensions from the end bearing 5 engages such ear 27 and such shaft 28 has an actuating hand wheel 29. By such means the flexible band 26 can be contracted around the pulley 25. When this is done, rotation of the drum 1 must be by actuation of the engine through the gear, but, when the pulley 25 is unclutched the sleeve 22 is loose,

thus permitting the gear to be carried around and the drum is released. This arrangement provides a free-wheel device obtainable at will.

5 From the foregoing it is clear that with the flexible band 26 contracted, the engine with its disks 9, 10 revolves around the fixed crank shaft 4, and motion is transmitted through the spur wheels 18, 19, 23 and 24 to 10 the drum 1. The drum 1 is provided with suitable flanges for the rope or cable. The diameters of the spur wheels are preferably so proportioned that the drum makes a less 15 number of revolutions than the rotating cylinders &c.

I carry the left-hand cheek of the drum 1 conveniently upon a sleeve 30 the inner end of which sleeve is bored to form a recess or chamber 31 into which is fitted a spring 32 20 which acts on a washer 33 (see Fig. 3) so disposed as to press against a tapered bush 34 fitted inside the boss of the disk 9 on the port side. This tapered bush 34 is thus under the influence of the spring 32 and is 25 prevented from independent rotation by a feather key 35. This tapered bush is self adjusting and automatically takes up any wear which occurs. Such bush 34 is drilled to 30 provide inlet and exhaust passage ways at three points 15^x, 16^x, and 17^x, for ingress and egress of fluid pressure, see the Figs. 3 and 4.

The hollow or port end of the fixed crank shaft 4 is cut with two passage ways 12 and 35 13 either of which may serve for inlet or exhaust, and, the fluid pressure is controlled by a simple D slide valve 36 fitted in the valve chest 37; the valve 36 is shown as 40 worked by rack and pinion gear 38 controlled by the handle 39. A dial 40 is fitted, over which a pointer 41 fitted on the shaft 42 works. Supposing, for example, that 45 passage 12 is for the time being the fluid pressure channel, then 13 is the exhaust channel. It is to be clearly understood, that, by reversing the slide valve, the drum 1 can be at once reversed; the passage 13 then becomes the fluid pressure channel and 12 the exhaust channel. I may use a rotary valve 50 in place of the D slide valve to control the fluid pressure.

As a modification in the manner of packing the rotatory disk with respect to the bored end of the fixed crank shaft I may 55 employ the arrangement shown by Figs. 5 and 6 where the sleeve 30^x is bored to produce a chamber 31^x in which is fitted two opposing cup leathers 43, 44, a channel 45 admitting fluid pressure between the two 60 leathers. The cup leather 44 presses against a ring 46 which abuts against a ball-race 47 intermediate of said ring and the tapered bush 34^x, such bush being similar to the one already described. I may apply cup leathers 65 48, at the points where the bush 34^x is bored

to provide passage ways for the fluid to and from the revolving cylinders. This allows the bush 34^x to be made an easy fit and permits "floating" to a slight extent.

I provide a suitable brake for the drum, 70 such as the brake strap 50 anchored as to one end at 51 and actuated by the foot-lever 52 fulcrumed at 53, the brake being normally held off by the spring 54.

Suitable provision is made to introduce 75 a supply of lubricant to the interior A of the drum to constitute an oil bath, so that, when the drum is at work all the inferior mechanism is lubricated by a splash system. Lubricant can be introduced by removing 80 one of the air boxes 56.

In order to allow any air pressure liberated through the holes 55, or leaking, to readily escape from the interior A of the drum I fit one or more removable air boxes 85 56 each having a baffle plate 57, which baffle plate while allowing the escape of air under pressure (through the holes 58) serves to a great extent to prevent the passage of oil 90 along with the air. Any or all of the parts 95 may revolve on ball bearings.

I declare that what I claim is.

1. A winding or haulage drum comprising a hollow revoluble drum, a stationary shaft, a gear wheel revoluble on said shaft adjacent one end thereof, the other end of said shaft being hollow, supports for such shaft, said shaft being provided with a fixed crank pin, a multi-cylinder motor housed in the drum and comprising revolving cylinders 100 and revolving disks, said gear wheel being operatively connected to one of said disks, movable pistons in said cylinders and piston rods working on the fixed crank pin, fluid supply passages, exhaust passages, external 105 valve gear controlling the fluid supply, and gear wheels operatively connected to said first mentioned gear wheel and to said drum and being all inclosed within the drum through which the motor actuates the drum, 110 as set forth.

2. A winding or haulage drum comprising a drum casing, a shaft support at one end, a fixed crank shaft support at the other end, a fixed crank shaft supported in said supports, a multi-cylinder motor, including revolving disks, and revolving cylinders and pistons within the cylinders, piston rods connecting the pistons with the fixed crank shaft, fluid supply and exhaust channels 115 in the fixed crank shaft support, a fluid control means outside governing the fluid pressure, and gear wheels within the drum casing and actuated by the motor, said gear wheels operatively engaging said drum, said gear wheels being disposed about the shaft support.

3. A winding or haulage drum having a drum casing, a solid shaft at one end, a bored crank shaft at the other, supports 120

therefor, a fixed crank pin, revoluble disks carried on said solid and said bored shafts, cylinders supported by the disks, pistons therein and connecting rods between the 5 pistons and fixed crank pin, inlet and outlet passages in the crank shaft, exterior fluid control devices, and means to pack the revoluble disk upon the bored portion of the fixed crank shaft comprising movable packing 10 pieces and a spring and gear wheels between the motor and drum and inclosed by the latter as described.

4. A winding or haulage drum comprising a drum casing, a shaft at one end, a fixed 15 bored crank shaft, supports for such shafts, revolving disks within the drum and supported on said shafts, a fixed crank pin, and converging cylinders around the crank pin, pistons in said cylinders and connecting rods connecting the pistons to the fixed crank pin, passage ways in the crank shaft, valve control gear external to the drum and controlling the fluid pressure, inclosed gear wheels actuated by the motor and by which the drum is rotated, a movable sleeve packing one of the disks and a spring holding the same up to its work, and movable covers on the drum casing, as described.

5. A winding or haulage drum comprising 30 a hollow drum, supports therefor, a stationary supporting shaft, a gear wheel adjacent one end thereof, said shaft being provided with a fixed crank pin, rotating disks supported by the shaft, multi-cylinders between

the disks, pistons in said cylinders operatively connected to said fixed crank pin, fluid supply channels cut in the other end of said fixed shaft, fluid control devices external to the drum, gear wheels within the drum operatively connected to said first mentioned gear wheel and actuated by the motor working around the shaft, said gear wheels driving the drum, a clutch arrangement in connection at the gear wheel end of the hollow drum, and means for clutching and unclutching the same, as described.

6. A winding or haulage drum comprising a hollow drum, supports therefor, a fixed crank shaft, rotatable disks thereon, converging cylinders supported by the disks, 40 pistons and piston rods within said cylinders and comprising a rotatable motor housed within the hollow drum, gear wheels within the drum and actuated by the motor, passage ways within one part of the crank shaft for 45 actuating fluid, and external control valve gear, and a clutch to free the drum, air escape contrivances fitted to the drum, and a brake device, all in combination and as set forth.

In testimony whereof I have signed my name to this specification in the presence of two subscribing witnesses.

CARL DAVENPORT.
